HEADGEAR GOOGLES

Charles E. Bowers, Chester, Pa., assignor to Fibre Metal Products Company, Chester, Pa., a partnership consisting of Frederick M. Bowers, Charles E. Bowers, and John W. Bowers

Application January 15, 1945, Serial No. 572,810

4 Claims. (Cl. 2—10)

1

This invention relates to so called headgear goggles and is concerned primarily with the mode of mounting a pair of goggles on a headgear.

A headgear goggles of the type with which this invention is concerned includes as essential elements a headgear and a pair of goggles. The headgear is adapted for snug fitting on the wearer's head and is intended to constitute the anchorage to which the goggles are attached. While the headgear is more or less permanently worn, that is, it will remain in position during the working day, the goggles will, from time to time, be swung from a protective position into an out of the way position above the wearer's forehead. In providing a means for attaching the goggles to the headgear so as to permit of the necessary manipulation, it is desirable that a high degree of simplicity be achieved and the number of parts held down to an absolute minimum. This not only assures of easy operation as the goggles are being moved, but eliminates any parts which might obstruct the vision.

Accordingly, this invention has in view as its foremost objective, the provision of a headgear goggles of the type aforesaid in which means is provided for operatively attaching the goggles to the headgear centrally of the goggles.

More in detail the invention has as its object the provision of a headgear goggles of the type noted in which the attaching means is secured to the bridge of the goggles.

In order to insure accurate fitting of the goggles, the goggle elements have been hingedly connected. In accordance with this invention a certain amount of relative pivotal movement between the individual goggle elements is permitted by the attachment to the headgear.

A further object of the invention is the provision, in a headgear goggles of the character described, of attaching means comprising a link having a pivotal connection at one end of the headgear and a pivotal connection at the other end, with the bridge of the goggles. Associated with each of the pivotal connections is means for generating friction which functions to maintain the goggles in an adjusted position.

Another important feature of the present invention resides in the particular means for connecting the attaching means to the goggles bridge. In accordance with this invention, the link is pivotally joined to a bracket and there is a pivotal connection between each individual goggle element and this bracket. Thus, each goggle element may be pivoted slightly with respect to the bracket. The hinged connection between the

2

goggle elements is of such a nature as to permit of this pivoting movement.

In an alternative form of the invention, an additional friction pivotal joint may be included in the link. This serves to facilitate the manipulation of the goggles.

Various other more detailed objects and advantages of the invention such as arise in connection with carrying out the above noted thoughts in a practical embodiment, will in part become apparent, and in part be hereinafter stated as the description of the invention proceeds.

The invention, therefore, comprises a headgear goggles, consisting of a headgear and a pair of hingedly connected goggle elements which are assembled by a link that is pivotally attached at one end to the headgear and at the other end to a bracket, which in turn is pivotally connected to each of the goggle elements. Frictional devices are associated with the pivotal connection at each end of the link to insure that the goggles will remain in an adjusted position.

For a full and more complete understanding of the invention, reference may be had to the following description and accompanying drawings, wherein:

Figure 1 is a view in front elevation of a headgear goggles made in accordance with the precepts of this invention;

Figure 2 is a detailed showing partly in section and partly in elevation of the attaching means which establishes the connection between the goggles and the headgear;

Figure 3 is a view in side elevation of the headgear goggles shown in Figure 1;

Figure 4 is a side view developing a modification; and,

Figure 5 is a front view of the modified form of the device shown in Figure 4.

Referring now to the drawings, wherein like reference characters denote corresponding parts and first more particularly to Figures 1, 2 and 3, the headgear goggles, of this invention, is shown as comprising the following essential elements:

A headgear identified in its entirety by the reference character H, a pair of goggles referred to generally as G, and the device which hingedly connects goggles G to the headgear H, which is referred to in its entirety by the reference character C.

The headgear H may take any of the forms now meeting with approval in this art. The invention has particularly in mind the use of a headgear which may be accurately adjusted to fit the head of any particular wearer. Thus, the headgear H

is shown as including a front part 10 which is of a skeleton formation defined by an arched cross-piece 11 and front rib 12 and a curved forepart 13. The latter may be provided with a sweat-band such as indicated at 14, in accordance with common practice. It is evident that this front part 10 is intended to be snugly fitted over the front part of the wearer's head. A rear headgear part is designated at 15 and as shown is pivotally attached to the front part 10 by the pivotal connections 16, there being a pivotal connection on each side. This rear part 15 is rendered adjustable in length by adjusting means shown at 17. Adjusting devices of this type are well known in this field and any such means of adjustment which is found satisfactory may be employed. It is evident that by availing of the adjusting device 17, the headgear H in its entirety, may be accurately fitted on the head of any particular wearer.

The goggles G are shown as comprising the individual goggle elements 18 and 19. The actual assembly of each of these elements 18 and 19 is not a particular part of this invention. Ordinarily each will include an outer protective glass which is replaceable and the inner ray-filter, which will protect the user's eyes from excessive light. The outer glass protects the ray-filter from flying particles of metal or other material which might damage the more expensive ray-filter. These glasses are removably contained in the circular frames illustrated. The frame of the goggle element 18 is shown as being provided with a lug 20 carrying hinge ears 21. The frame of the goggle element 19 is provided with a lug 22 which carries hinge ears 23 that are complementary and interfit with the ears 21. A hinge pin 24 passes through aligned openings in the ears 21 and 23 to establish the hinge connection. It is notable that there is a loose fit between this hinge pin and the ears. This looseness permits the adjustment which will later be described.

The connecting attachment C includes a bracket 25 which extends across the top faces of the lugs 20 and 22. At one end the bracket part 25 is pivotally joined to the lug 20 by the pivot screw shown at 26. At the other end the bracket 25 is pivotally joined to the lug 22 by the pivot screw shown at 27. It is evident that the pivotal connections 26 and 27 between the bracket 25 and the lugs 20 and 22 formed on the individual goggle elements, together with the looseness in the hinge joint defined by the hinge pin 24 and openings in the ears 21 and 23, permits a certain amount of angular adjustment between the individual goggle elements 18 and 19.

Included as a part of bracket 25 are a pair of spaced ears 28. Another bracket 29 is permanently secured to the headgear H by rivets shown at 30 which securely anchor the bracket 29 to the front part 10 of the headgear. This bracket 29 also carries a pair of spaced ears 31 and the spacing of these ears corresponds to the spacing of the ears 28.

A connecting link L is made up of two complementary halves 32 and 33. At one end the link L is positioned between the ears 31 and pivot pin 34 passing through aligned openings in the ears 31 and halves 32 and 33 establishes the pivotal connection. It will be noted that the openings through the link halves 32 and 33 are enlarged as shown at 35 to provide a counterbore which receives an expansion spring 36. This expansion spring tends to spread the link halves apart and press them against the inner faces of the ears 31

and thus create a required amount of friction. The other end of the link L is similarly positioned between the ears 28 and the pin 37 and establishes the pivotal connection in the manner above described. A spring 38 will also be located in a counterbore 35 and disposed about the pin 37 to generate friction at that end of the link.

With the device thus described, it is apparent that suitable provision is made for angularly adjusting the goggle elements so that they will snugly fit about the eyes of the wearer. The friction created at the pivots 34 and 37 serves to maintain the goggles either in a protective position in front of the wearer's eyes or in an out of the way position above the wearer's forehead. The goggles may be moved by grasping them at any convenient part, such as one of the handles shown at 9, and the central location of the connection to the headgear renders such manipulation a matter which is easily carried out. Moreover, the anchorage to the headgear is firm and secure and will not be impaired by continued use of the device.

Figures 4 and 5 illustrate a modified form of the invention in which the connection between the headgear H and goggles G is shown as including an additional pivotal connection. Thus, the pivotal connection at 34 to the bracket 29 on the headgear remains the same as does the connection at 37 to the bracket 25 on the goggles G. However, between the pivots 34 and 37 the structure is changed from the form shown on Figures 1, 2 and 3. A link identified as 1 is secured at one end to the pivot pin 34 in the manner above described, and a second link 11 is connected at one end to the pivot 37. These links 1 and 11 are formed of complementary halves as above described in connection with the link L and are joined together intermediate the pivots 34 and 37 by another pivot pin 38. This pivot pin 38 may also be provided with a spring for creating friction as above described in connection with pivots 34 and 37. The purpose of this additional pivotal joint in the connection C is to facilitate the manipulation of the goggles G with respect to the headgear H as it provides a variety as to adjustment and number of positions which are obtainable in excess of that provided by two pivotal joints.

While preferred specific embodiments of the invention are hereinbefore set forth, it is to be clearly understood that the invention is not to be limited to the exact construction illustrated and described because various modifications of the details may be provided in putting the invention into practice within the purview of the appended claims.

What is claimed is:

1. In a headgear goggles, a bracket adapted to be mounted on a headgear and formed with a pair of spaced ears, a second bracket adapted to be mounted on a pair of goggles and provided with a pair of spaced ears, a link consisting of complementary halves and having one end disposed between the ears on said first bracket and the other end disposed between the ears on said second bracket, said ears and said link halves having aligned openings, the openings in said link halves having counterbores, pivot pins passing through said aligned openings, and expansion springs disposed about said pivot pins in the counterbores for urging said link halves against said ears to create friction.
2. In headgear goggles, means for attaching a pair of goggles to a headgear, said means comprising: a link consisting of complementary halves

which are formed at each end with aligned openings having counterbores, a pivot pin passing through said aligned openings at one end, an expansion spring disposed about said pivot pin in the counterbores of said link, a bracket, means for attaching said bracket to a pair of goggles, ears on said bracket enclosing the other end of said link and formed with openings in alignment with said openings in said link, a pivot pin passing through said aligned openings in said ears and said link, an expansion spring about said pivot pin and located in said counterbores in said link, a second bracket, means for attaching said second bracket to a headgear, and a pivotal connection between said second bracket and one end of said link.

3. In a headgear goggles, a bracket adapted to be mounted on a headgear and formed with a pair of spaced ears, a second bracket adapted to be mounted on a pair of goggles with a hinge in the center to allow lateral movement and provided with a pair of spaced ears, a link consisting of complementary halves and having one end disposed between the ears on said first bracket and the other end disposed between the ears on said second bracket, said ears and said link halves having aligned openings, the openings in said link halves having counterbores, pivot pins passing through said aligned openings, and expansion springs disposed about said pivot pins in the counterbores for urging said link halves against said ears to create friction.

4. In a headgear goggles, a bracket adapted to be mounted on a headgear and formed with a pair of space ears, a second bracket adapted to be mounted on a pair of goggles and provided with a pair of space ears, two links arranged end to end each consisting of complementary halves and having one end of the first link disposed between the ears of said first bracket and the other link having its other end disposed between the ears of said second bracket, said ears and said link halves having aligned openings at each end, the openings in said link halves having counterbores, pivot pins passing through said aligned openings, and expansion springs disposed about said pivot pins in the counterbores for urging said link halves against said ears to create friction.
